SUPERVISORY SYSTEM FOR WATCHMEN

John H. Derby, Scarsdale, N. Y., assignor of one-third to Charles F. Kelley, Brooklyn, N. Y., and one-third to Halford W. Park, New York, N. Y.

Application February 12, 1936, Serial No. 63,492

5 Claims. (Cl. 161—20)

This invention relates to systems for keeping a check on the activities of watchmen, and particularly to systems which give an alarm provided the watchman has failed for a predetermined length of time to operate a switch or other controlling device along the path of his tour of duty. Alarms of this character, which are sometimes designated "delinquency alarms", have usually been associated with complicated watchmen's supervisory systems which make records of the watchman's movements, or have been too complicated in themselves or have been too unreliable in their operation or have required too much attention to keep them in working order to permit them to go into extensive use. There are thus today thousands of buildings, such as office buildings and industrial plants, in which watchmen are employed, where the only check on the activity of the watchman is that obtained after he has completed his tour of duty or, in many cases, after he has left the premises altogether. In many cases also watchmen are employed where no record whatever is kept of their activities and therefore even the satisfaction of knowing the next day that they have been doing their duty is denied the building or plant owner.

A general object of the present invention is to provide a simple, comparatively inexpensive and thoroughly reliable means for giving an alarm both when something happens to a watchman which may prevent his attending to his duties and when he merely fails to perform his duties. The protection afforded a property by a watchman depends fully as much upon his physical ability to make his rounds as upon his faithfulness to his duty. In the absence of a signal of the delinquency type, accident, injury, sickness, death or "hold-up" may leave a manufacturing plant or other building unguarded for many hours with no knowledge by anyone of this failure of the watch patrol. This not only is liable to cause serious loss to the owner or owners of the plant, but it is unfair to the watchman and may result in serious injury or even death to him by reason of the delay in advising others of his disability.

The simplest form of watchmen's supervisory service employed at the present time is a clock which is carried by the watchman from station to station and in which a record may be made by keys located at the respective stations. This clock provides an effective means of determining whether or not the watchman has made his complete rounds and the succession of the stations that he has visited, but it affords the watchman himself no protection whatever while on duty and

it does not insure to the building owner immediate notification of any injury to or delinquency of the watchman. A further object of the present invention, therefore, is to provide a simple, reliable, easily installed and comparatively inexpensive system that will supplement the protection afforded the building owner by the usual watchman's clock.

An important feature of the present invention is the provision of a synchronous motor for driving the time control mechanism which can automatically be brought into operation as an incident to starting the watchman on his tour of duty and which can automatically be stopped as an incident to his completion of his tour of duty, as, for example, when the watchman returns to his chief the watchman's clock or other implement handed him when starting his tour and this is replaced in its custodial cabinet.

Another important feature of the invention is the provision of means for automatically giving an alarm when the watchman, either under compulsion or with a view to beating the apparatus, holds the alarm intercepting switch closed more than momentarily.

Other objects and important features of the invention will appear from the following description and claims when considered in connection with the accompanying drawings, in which—

Figure 1 is a horizontal section through the casing in which apparatus embodying the present invention is normally sealed, this view showing the apparatus partly in plan and partly in section;

Figure 2 is a vertical section through the casing, showing the parts which are located on the front of the insulating panel;

Figure 3 is a vertical section through the casing, showing the parts which are located on the rear of the insulating panel, some of these parts being shown in section;

Figure 4 is a section on the line 4—4 of Fig. 3;

Figure 5 is a front elevation of a cabinet which encloses the casing in which the apparatus is normally sealed, the cabinet being open to show the location of the casing therein and also the support for the ordinary watchman's time clock;

Figure 6 is a view of the cabinet similar to that shown in Figure 5, but with the casing containing the apparatus removed therefrom and the compartment for the lead-in wires shown in section;

Figure 7 is a transverse section through the cabinet shown in Figs. 5 and 6, with the casing in position therein;

Figure 8 is an enlarged detail section of that

part of the cabinet and the associated part of the casing in which the receptacle and the corresponding plug are respectively located;

Figures 9 and 9A are detail views of the operating mechanism of one of the resetting switches, and

Figure 10 is a wiring diagram.

The apparatus of the present invention is preferably enclosed in a sealed casing 2, of aluminum or other suitable material, so that it may be bodily inserted in and removed from a cabinet 4 provided with a door 6 that can be locked if desired. The purpose of this, as will appear hereinafter, is to permit the bodily replacement of the apparatus by another in good working order provided the one originally installed requires service, thus insuring uninterrupted supervision of the watchman.

The operative parts of the supervisory mechanism are shown as mounted upon an insulating panel 8, of bakelite or other suitable material, which is positioned vertically in the casing 2 and is maintained in its vertical position by guides 10 riveted to the end walls of the casing 2. The supervisory mechanism itself consists essentially of a synchronous motor arranged to be connected to the alternating current with which the building in which the apparatus is to be installed is supplied, practically all public service alternating supplies being now provided with master clock controls to insure their uniform operation over extended periods of time, and means operated from the synchronous motor for closing an alarm circuit after a predetermined period of elapsed time from the starting of said means, provided the watchman, whose activities are being supervised, does not do something to reset said means to its starting point and thus prevent the closing of the alarm circuit.

In the illustrative embodiment of the invention the field part of the synchronous motor is mounted upon the frame 12 which is carried on the front face of the panel 8 and the rotor 14 of the synchronous motor is provided with a shaft 16 mounted in bearings 18 and 20, the shaft 16 extending through the panel 8 and being provided on its rear end with a worm 22 which engages a worm wheel 24 having a hub 26 clamped upon a shaft 28 mounted in bearings in a frame 30 attached to the rear face of the panel 8.

The shaft 28 carries at its other end a disk 32, recessed to receive one member 34 of a face clutch, said member 34 being formed of rubber or other suitable clutch facing material. The other member 36 of the clutch, of similar material, is carried by a cylinder 38 of insulating material, such as bakelite, upon which the alarm circuit closers hereinafter to be described are carried. The cylinder 38 is provided with a central threaded bushing 40 which receives one threaded end of a rod 42, the other end of which is provided with a spacing nut 44 and a lock nut 46, primarily for assembling purposes.

The rod 42 extends through the hollow core 48 of an electromagnet 50 having an enclosing casting 52 attached to the rear face of the panel 8. The core 48 of the magnet 50 has its end remote from the cylinder 38 closed to provide a bearing in which the rod 42 can both turn and slide and the bushing 40 of the cylinder 38 has a hub extension which fits into the open end of the core 48 to form a second bearing for the rotary parts to insure their turning about the axis of the rod 42.

At its end adjacent to the electromagnet 50 the cylinder 38 carries an armature 54 which is nor-

mally held away from the electromagnet 50 by a spring 56 coiled about the rod 42 within the magnet core 48, the spring 56 having one end 58 inserted in a hole in the closed end of the armature core 48 to hold it against turning with respect to the armature core and having its other end 60 inserted in a socket in the bushing 40 so that the spring may be helically tensioned or wound up as the cylinder 38 is turned with the driving shaft 28 when the clutch members 34 and 36 are in clutching relation to each other.

It will be seen that when the electromagnet 50 is not energized the spring 56 will hold the clutch members 34 and 36 in clutching relation to each other and the cylinder 38 will be turned with the shaft 28, which in turn is driven from the synchronous motor through the shaft 16, worm 22 and worm wheel 24. When, however, the electromagnet 50 is energized the armature 54 carried by the cylinder 38 will be attracted toward the magnet against the longitudinal tension of the spring 56, the clutch members 34 and 36 will be separated and whatever additional tension has been put upon the spring 56 by the winding up thereof will be permitted to act to rotate the cylinder 38 in the reverse direction until the stop member 62 carried by the cylinder engages the stationary stop 64. Preferably, of course, there will be some initial tension on the spring 56 about its axis which will cause it to maintain the stop member 62 against the stop member 64 when the parts are at rest and which will tend to accelerate the return movement of the stop member 62 into engagement with the stop member 64.

In the illustrative embodiment of the invention provision is preferably made for two alarms, one a warning alarm to the watchman to advise him that he has not operated the resetting mechanism, and a second delayed alarm, preferably sent to some place outside the building, which will usually indicate that the watchman has been disabled or otherwise prevented from operating the resetting mechanism and that the situation should be investigated. It will be understood, of course, that the periodicity may be selected to suit particular conditions, that is, the time interval before the initial alarm may be anything desired and the interval between the initial warning alarm and the final distress alarm may also be selected to suit the particular conditions. A suitable periodicity is a 15 minute period between the starting of the circuit-closing cylinder and the closing of the initial alarm circuit, unless the watchman in the meantime resets the cylinder to its starting position, and a period of 10 minutes between the initial alarm and the outside alarm in the event that the watchman either fails to or is unable to heed the warning signal.

In the illustrative embodiment of the invention the circuit closer for the initial alarm is shown as a metal insert 66 located, as shown in Fig. 4, about 90° from the circuit terminals to be bridged, the cylinder 38 being geared to make a 90° rotation in fifteen minutes. The circuit closer 66 is arranged to bridge the two terminals 68 and 70, 70 being a line terminal common both to the initial alarm circuit and to the emergency alarm circuit. The circuit closer 66, as will be seen from Figure 3 of the drawings, extends across the outer face of the cylinder 38, that is, lengthwise of the axis thereof only far enough to bridge the terminals 68 and 70 and not to engage the terminal 72 of the emergency alarm circuit. To close this circuit, that is, to bridge the terminals 70 and 72, a second circuit closer 74 is provided which is so

located on the cylinder 38 that it will bridge only the terminals 70 and 72 and will not bridge the terminals 70 and 68.

To prevent continued rotation of the cylinder 38 after both the warning alarm and the emergency alarm have been sounded, which might result in breakage because of the stops 62 and 64, means is provided for opening the circuit in which the synchronous motor is located, thereby 5 stopping the motor after the cylinder has completed substantially a half rotation. The illustrative means comprises two switch members 76 and 78 in the current supply to the motor, the switch member 78 having a finger 80 adapted to 10 engage and ride on the cylindrical surface of the cylinder 38 and when thus riding on the outer periphery of said surface acting to hold the switch member 78 in circuit closing relation to the switch member 76, the switch member 78 being carried by a spring so tensioned that it 15 tends to move the switch member 78 away from the switch member 76, when permitted to do so. The cylinder 38 is provided with a depression 82 in the path of movement of the finger 80 of the switch member 78 over the surface of the cylinder and when this depression 82 comes beneath the finger 80 it permits the switch member 78 to move away from the switch member 76 and thus 20 open the motor circuit, thereby stopping the synchronous motor and stopping the rotation of the cylinder 38.

The electromagnet 50 is in a normally open circuit which includes a series of switches 84 arranged in parallel and located at different stations along the path traversed by the watchman in performing his tour of duty, one of these switches being illustrated in detail in Figures 9 and 9A of the drawings. Closing of any one of the switches 84 will close a circuit through the 25 electromagnet 50 and energize the magnet to attract the armature 54, thus releasing the clutch members 34 and 36 from engagement with each other and permitting the spring 56 to return the cylinder 38 to its starting position, with the stop 30 62 in engagement with the stop 64.

To insure long life of the switches 84 and to insure that a complete switch closing movement will be effected by the watchman when he visits each of the stations at which the switches are located, each switch is preferably constructed as 35 shown in Figures 9 and 9A. For convenience in installing the switches each is located in an iron box 86 provided with a cover 88 held in place by screws 90 preferably riveted at their rear ends, the cover 88 being preferably formed of brass to receive a brass plate 92 of a "Yale" lock casing 93 which is preferably permanently attached to the plate 88, as by soldering thereto. The rotary barrel 94 of the lock extends beyond 40 the rear end of the lock casing 93 and is provided with a ratchet wheel 96 engaged by a ratchet 98 mounted on a pin or bolt 100 carried by a bracket 102 on the lock casing. The purpose of the pawl and ratchet is to prevent the lock from being 45 turned backwards and to require a complete turn of the key in the lock before it can be removed, after the watchman has started to turn the lock, thereby insuring first closing and then opening.

Mounted on a second stud or pin 104, carried 50 by the bracket 102 on the lock casing 93, is a plate 108 provided with a slot 110 into which a pin 112 projects from the ratchet wheel 96 on which it is eccentrically located. The revolution of the pin 112 about the axis of the ratchet wheel 55 96 oscillates the plate 108 between the two dotted

line positions shown in Fig. 9. A mercury tube switch 114 is carried in a clamp 116 attached to the upper edge of the plate 108 and, as shown in Fig. 9A, in its normal position is so tilted that the mercury in said tube is at the end of said tube 60 remote from the switch terminals 118 and 120. In other words, when the lock is in the position to permit the key to be removed the switch 114 is in its open circuit position.

When the key 117 is inserted in the lock and the barrel 94 is turned in a clockwise direction as viewed from the front, or in a counter-clockwise direction as viewed from the rear, the movement of the pin 112 in the slot 110 of the plate 108 oscillates the plate 108 on the stud 104 so that the tube 114 is tilted to bring the mercury into circuit-closing relation to the switch terminals 118, 120 and then is tilted back to its initial position in which the mercury is at the end of said tube 65 remote from said terminals.

Should the watchman make a half turn of the key in the lock so that the mercury bridges the terminals 118 and 120 and then leave the key in this position with a view to causing the magnet 50 to remain energized, thereby preventing the 70 turning of the cylinder 38 with the shaft 28, the current flowing through the circuit thus closed will flow through a heating coil 122 included in a shunt of said circuit. The heating coil 122 is connected to and also surrounds a thermostatic couple 124 which constitutes one member of a thermostatically operated switch, the other member 126 of which is stationary. As the thermostatic couple 124 is heated up by the flow of the current through the coil 122 and through the couple itself the difference in the coefficients of expansion of the two metals making up the couple 124 will cause the switch member 124 to bend into contact with the switch member 126 and thus close the circuit to an outside alarm.

To insure automatic starting of the supervisory mechanism when the watchman starts on his tour of duty, a switch is provided for closing the circuit to the synchronous motor, which switch is normally pressed towards closed position and is preferably held in open position by the weight of some article such as the watchman's time clock which is handed to him when he starts his tour of duty. As herein shown, the automatic switch comprises a stationary switch member 128 and a movable switch member 130 tending normally to move to open switch position and a lever fulcrumed at 132 and having a switch-engaging arm 134 engaging said movable switch member and a hook arm 136 on which the watchman's clock, or other article providing the required weight, is hung. A spring 138 engaging the arm 136 tends to move said arm 136 up whenever the weight is removed from said arm thus causing the arm 134 to move the movable switch member 130 into engagement with the stationary switch member 128 and close the circuit to the synchronous motor, thereby starting the supervisory mechanism. In Figures 5 and 7 a watchman's clock 140 is shown as hung from the hook arm 136.

In Figure 10 is shown the diagram of the wiring of the supervisory mechanism and of the control stations and also of the warning alarm and the emergency alarm. Current for the apparatus is taken from the alternating current supply for the building through wires 142 and 144 going through a fuse box 146 to terminals 148 and 150 on a separate panel 152 contained in a chamber in the upper back part of the cabinet 4, said 75

- chamber being partitioned from the remainder of the cabinet by a bottom wall 154 and a side wall 156 and being provided with a removable cover 158. From the panel terminal 148 connection is made to one of the motor terminals through wire 160, wire 162, switch member 78, switch member 76 and wire 164. From the panel terminal 150 connection is made to the other motor terminal through wire 168.
- 10 Current to operate the warning alarm 170 is carried to the common alarm terminal 70 from the panel terminal 148 through a wire 172. The other terminal 68 of the warning alarm circuit is connected by wire 174 to panel terminal 176 which in turn is connected by wire 178 to one side of the alarm 170, the other side of the alarm 170 being connected by a wire 180 to panel terminal 182 which in turn is connected by a wire 184 to the panel terminal 150, thus completing a circuit from the positive to the negative side of the current supply whenever the circuit closer 66 on the cylinder 38 bridges the terminals 68 and 70.
- 15 The circuit through the emergency alarm 186 includes the wire 172 from the positive side of the circuit to the common alarm terminal 70 and the wire 188 from the terminal 72 to the panel terminal 190, the wire 192 from the panel terminal 190 to one side of the alarm 186, the wire 194 from the other side of the alarm 186 to the panel terminal 182, and the wire 184 from the panel terminal 182 to the panel terminal 150, thus coming back to the negative side of the circuit. The alarm 186 will, therefore, be operated whenever the circuit closer 74 on the cylinder 38 bridges the terminals 70 and 72.
- 20 To prevent the giving of the warning alarm by the closing of the circuit through the alarm gong 170 and also to prevent the giving of the emergency alarm by the closing of the circuit through the alarm gong 186, the watchman will periodically close a station switch 84, of which there are a series located along the path of his tour of duty, in order to energize the magnet 58 and thus unclutch the clutch members 34 and 36 and permit the spring 56 to return the cylinder 38 to its starting position. The circuit through the magnet 58 comprises the wire 169 from the terminal 148 on the positive side of the electric circuit and the wire 196 and the wire 198 to a second panel terminal 200 to which one side 202 of the station switch circuit is connected, the other side 204 of said station switch circuit being connected to another panel terminal 206 which is connected by the wire 208 to the panel terminal 182 and thus through the wire 184 to the panel terminal 150 on the negative side of the circuit. Closing any one of the switches 84 which are in parallel will complete a circuit through the magnet 58 and thus energize said magnet and cause the opening of the clutch between the driving shaft 28 and the cylinder 38.
- 25 In the event that any one of the switches 84 is left closed more than temporarily the coil 122 and thermostatic couple 124, which are in a shunt 209 about the magnet 58, will have a sufficient flow of current through them to heat up the thermostatic couple 124 and cause it to engage the other member 126 of a switch which will complete a circuit to the emergency alarm 186.
- 30 This circuit will be made up as follows: Starting from the panel terminal 148 on the positive side of the current supply, the current will flow through the wire 160, the wire 210, the thermostatic couple 124, the switch member 126, the wire 212, the panel terminal 190, the wire 192 to

one side of the gong 186, the wire 194 from the other side of the gong 186, the panel terminal 182 and the wire 184 back to the panel terminal 150 on the negative side of the circuit.

For convenience in removal of the casing 2 from the cabinet 4 the electrical connections between the terminal on the panel 152 and the apparatus on the panel 8 are completed by means of a plug 214 provided with seven terminal pins 216 adapted to enter a corresponding seven terminal 10 sockets 218 in a socket member 220, said plug 214 being screwed into a housing 222 on the rear wall of the casing 2 and being provided with studs 224 to which the wires from the panel 8 can be attached. 15

It will be seen that the housing 222 fits over the socket 220 and serves, together with a central guiding stud 226, to guide the pins 216 into the corresponding sockets 218 of the receptacle 220 thus permitting the casing to be removed and inserted without disconnecting the wiring. 20

To permit observation of the apparatus, that is, to permit the superintendent of the watchmen to see whether or not the apparatus is in operation, a window 228 is provided in the casing 2 opposite the synchronous motor so that the superintendent can look into the casing and see whether or not the motor is rotating. 25

What is claimed as new is:

1. In a delinquency alarm system, an alarm circuit including a warning signal, a patrol circuit having a switch therein, chronometrically operated means for energizing said alarm circuit if the switch in said patrol circuit is not operated within a predetermined period, and an emergency 35 alarm circuit including an emergency alarm arranged to be energized from said chronometrically operated means within a predetermined time after the alarm circuit has been energized, said chronometrically operated means including a 40 synchronous motor and a circuit breaker in the motor operating circuit operated from said motor after said emergency alarm has been energized.

2. In a delinquency alarm system, an alarm circuit including a signalling device, a patrol circuit having a switch therein, chronometrically operated means for energizing said alarm circuit when the switch in said patrol circuit has not been closed within a predetermined period and a thermostatically operated switch for energizing said alarm circuit independently of chronometrically operated means when the switch in the patrol circuit is left in closed position, the thermostatic operation being effected by heat generated by the current in the patrol circuit. 55

3. In a delinquency alarm system, an alarm circuit, including a signalling device and chronometrically operated means for energizing said alarm circuit, at the end of a predetermined interval of time after said means has been actuated, comprising a chronometrically driven shaft, a second shaft coaxial with, movable lengthwise into clutching-relation to and normally clutched to said driven shaft, appropriate clutch members being carried by said shafts, alarm circuit closing means rotatable with said second shaft into circuit-closing position and a spring on said second shaft tensioned both to maintain said shafts yieldingly in clutching relation to each other and to reversely rotate said second shaft to its starting position when said shafts are unclutched, and means for automatically stopping said chronometrically operated means after a predetermined rotation of said second shaft when said shafts remain clutched to each other. 70 75

4. In a delinquency alarm system, an alarm circuit having a signalling device therein, a patrol circuit having a switch therein, a chronometrically driven shaft, a second shaft coaxial with, 5
movable longitudinally into clutching relation to and normally clutched to said driven shaft, appropriate clutch members being carried by said shafts, alarm circuit closing means carried by said second shaft, a spring on said second shaft 10 tensioned to maintain said shafts yieldingly in clutching relation to each other and to reversely rotate said second shaft to starting position when said shafts are unclutched, and a magnet in said patrol circuit arranged when energized to move 15 said second shaft against the tension of said spring into unclutched relation to the driven shaft, said second shaft and its spring being coaxial with said magnet and mounted within the core thereof.

20 5. Chronometrically operated means for closing

an alarm circuit within a predetermined period after said means has been actuated, comprising a rotatable cylinder having a circuit closer thereon and having a magnet armature at one end thereof, a shaft on which said cylinder is mounted having a helical spring thereon so anchored and so connected thereto as to be tensioned both longitudinally and helically, a magnet, within the core of which said shaft has bearings permitting it to move both longitudinally and rotatably, respectively against the longitudinal tension of said spring and against the helical tension thereof, and a chronometrically driven shaft to which said cylinder shaft is adapted to be clutched by the action of said spring when said magnet is not energized, appropriate clutch members being carried by said shafts, said spring being also confined within said magnetic core.

JOHN H. DERBY. 20
